UNITED STATES PATENT OFFICE.

DANIEL B. DAVIS AND JOSIAH J. FISHER, OF LARAMIE, WYOMING TERRITORY.

CAR-CO尤LING.

SPECIFICATION forming part of Letters Patent No. 395,040, dated December 25, 1888.

Application filed March 30, 1888. Serial No. 268,984. (No model.)

To all whom it may concern:

Be it known that we, DANIEL B. DAVIS and JOSIAH J. FISHER, of Laramie, in the county of Albany and Territory of Wyoming, have 5 invented a new and Improved Car-Coupler, of which the following is a full, clear, and exact description.

Our invention relates to a car-coupler, and has for its object to provide a means of coupling cars without passing between the same, and also to provide a means whereby the draw-head may be elevated vertically or adjusted laterally, as desired, from the sides of the car.

15 A further object of our invention is to provide a means for sustaining the coupling-pin in an elevated position when the cars are uncoupled.

The invention consists in the construction 20 and combination of the several parts, as will be hereinafter described, and fully set forth in the claims.

Reference is to be had to the accompanying drawings, forming a part of this specification, 25 in which similar figures of reference indicate corresponding parts in all the views.

Figure 1 is a partial perspective view of a car having our coupler attached. Fig. 2 is a central vertical section through the coupler, 30 and Fig. 3 is a bottom plan view of the same attached to a car.

The draw-head 10 is supported centrally beneath the car by means of a draw-bar, 11, attached to the rear end of the draw-head and 35 projected through an aperture, 12, in a transverse beam, 12^a, secured to the floor of the car, as best illustrated in Fig. 2. The aperture 12 is of greater diameter upon the outer face of the beam than upon the inner face, 40 and is so constructed to admit of a limited vertical and lateral movement of the draw-head, as will be hereinafter set forth. The draw-bar is secured in position by means of a washer to the rear of the beam and a nut 45 engaging the washer. Between the beam and the draw-head a spring, 13, is coiled upon the draw-bar, whereby when the cars are coupled and the opposing draw-heads meet the strain will be removed from the draw-bar.

50 The draw-bar is provided with a central

longitudinal bore, 14, and the usual pin-opening, 15, leading into said bore. Within the bore, a block, 16, is held to slide, which block is preferably cylindrical, and from its rear end a coil-spring, 17, is projected, having a 55 bearing against the rear wall of the bore 14. The block 16 is provided at the front, upon the under side, with an angular recess, 18, whereby a lip, 19, is obtained.

The draw-bar projects beyond the sill of 60 the car, and is surrounded by a rectangular frame, 20, consisting of a buffer-block, 21, parallel side pieces connected to said buffer-block and the rear beam above referred to, in which the end of the draw-bar is pivoted, 65 and a strap, 27, connecting the under sides of the beam at the front. The forward end of the draw-bar is of greater height than the remaining portion, the projection thus produced being adapted to engage the buffer-block when met by an opposing draw-head. 70 This portion of the draw-head may also be utilized to carry an extra link by producing a suitable cavity therein above the bore 14.

Upon the front of the draw-head a vertically-projecting plate, 22, is attached or cast integral therewith, the rear face of which plate is in alignment with the pin-aperture, the purpose of the front plate being to support the coupling when said pin is held in its 80 normal or elevated position, as illustrated in Fig. 2.

A shaft, 23, is projected above the sill of the car transversely the ends, and held to slide and turn in suitable bearings, 24, as best 85 shown in Fig. 1. When the shaft 23 approaches the center of the car, it is carried downward and transversely beneath the car and upward to form a yoke, 25, which yoke is adapted to surround or embrace the draw-bar. The ends of the shaft 23 may be provided with cranks 26 or a wheel or any form of grip device desirable.

In operation, when the draw-bar is at rest or when the car is uncoupled, the block 18 is 95 carried rearward, the coupling-pin inserted in its aperture, and retained in said aperture above the link-opening by engaging with the lip 19, as shown in Fig. 2; or the block 18 may be suffered to extend as far to the front as 100

the spring will admit and the coupling-pin be allowed to rest upon the upper surface of the block 18. In either event, when the draw-head is met by an opposing draw-head the 5 link, entering the bore 14 and engaging the surface of the block beneath the lip 19, propels the said block rearward, which action, releasing the coupling-pin, allows it to drop down and pass through the link, effecting a 10 coupling.

If the opposing draw-head is of greater height than the one to be coupled with, by means of the shaft 23 the latter draw-head may be elevated to meet the opposing one; 15 or, if the opposing draw-head is not centrally located, by pulling or pushing upon the shaft 23, as occasion may demand, the two draw-heads may be brought to align one another. It is obvious that the coupling may be effectually accomplished without the necessity 20 of the operator passing between the cars.

Having thus fully described our invention, we claim as new and desire to secure by Letters Patent—

1. The combination, with a draw-head provided with a pin-opening and a vertical face projection in front of the pin-opening, of a spring-actuated block held to slide within the same and recessed upon the under side at the front to receive a link, a coupling-pin adapted 25 to be normally supported by the block, and means, substantially as shown and described, for manipulating the draw-head vertically or laterally, as and for the purpose specified.

2. The combination, with the body of a car, 30 of a draw-head supported beneath the car to have a limited lateral and vertical movement and a transverse shaft loosely held in engagement with the end of the car, provided with a central yoke embracing the draw-head, substantially as shown and described, and for the purpose specified.

DANIEL B. DAVIS.
